WELL PUMP

Charles F. Moseley, Bartlesville, Okla.

Application February 2, 1940, Serial No. 317,031

3 Claims. (Cl. 103—179)

This invention relates to new and useful improvements in pumps for deep wells, and more particularly, but not by way of limitation, to an improved arrangement of the standing valve of the pump.

Bottom hole oil pumps or "working barrels," as they are commonly known in the oil industry, are usually secured to the lowermost section of well tubing by a threaded collar or the like. The pumps are actuated by a string of sucker rods suspended in the well tubing. Heretofore the standing valve spider in a conventional working barrel has been positively or directly connected to the working barrel housing by an annular shoulder, threads, or the like. In this manner there is a direct connection between the well tubing and the standing valve spider, and upon a downward movement of the working barrel plunger by the sucker rods to close the standing valve, all the weight of the oil previously pumped into the tubing acts upon the standing valve. This oil weight has a very detrimental effect in causing an elongation or stretch of the steel tubing sections disposed in the casing of the well hole, which in turn causes a shortening of the plunger stroke of the working barrel. Furthermore, well holes are usually irregular or crooked, and in view of this the normally spaced tubing will contact the casing at various points. The oil weight in stretching the tubing causes a detrimental wear of the tubing by the frictional drag against the casing at the points of contact.

It is therefore an important object of this invention to eliminate the direct connection between the standing valve spider of a working barrel and the well tubing.

Another object of this invention is to provide a floating connection between the standing valve spider of the working barrel housing in order that the weight of the oil pumped into the tubing will not stretch the tubing.

And still another object of this invention is to provide a means for anchoring a standing valve of a working barrel independent of the working barrel housing in order to eliminate considerable strain and stretch of the sections of well tubing and prevent frictional drag against the casing.

And a further object of this invention is to anchor a standing valve of a working barrel in a well hole, separate from the barrel housing, yet provide means where said standing valve and anchor can be easily pulled from the well hole.

Other objects and advantages of the invention will be evident from the following detailed description read in conjunction with the accom-

panying drawings which illustrate one form of my invention.

Fig. 1 is a fragmentary sectional elevation of the preferred embodiment of the invention shown disposed in a well hole.

Fig. 2 is a view similar to Fig. 1 showing the pump unit being pulled from the well.

Fig. 3 is a sectional elevation of the lower part of the pump showing a modification for the standing valve arrangement.

Fig. 4 is an enlarged fragmentary sectional elevational view of a modification of the standing valve anchor.

Fig. 5 is a view taken on lines 5—5 of Fig. 3.

15 Referring to the drawings in detail, and more particularly to Fig. 1, reference character 2 designates the casing of a well hole in which is disposed the usual tubing 4. The pump or working barrel housing 6 is secured to the lowermost section 10 of tubing 4 by a threaded collar 8. The pump housing 6 includes the usual apertured plunger 10 provided at its uppermost portion with an integral valve spider 12. The spider 12 is provided with a threaded projection 14 adapted to be secured to a string of sucker rods (not shown) for actuating the pump plunger. The top most portion of the plunger 10 is provided with a recess 16 acting as a valve seat for a ball valve 18 disposed within the spider. The valve 18 is usually termed the travelling valve and cooperates with the seat in closed position.

A standing or inlet valve is disposed in the lower portion of the housing 6 and comprises a spider 20, ball valve 22 disposed therein and cooperating with a recessed portion providing a seat 24 for the ball. It will be apparent from Fig. 1 that the spider 20 includes cylindrical member 26 extending below the seat 24 to be threadedly connected at 28 to an apertured seat anchor 30 disposed below the housing. The outer periphery of the cylinder 26 is provided with an annular shoulder 32 for supporting suitable packing 34 anchored between the cylinder 26 and housing 6 to prevent leakage of displaced oil.

45 The seat anchor 30 is provided with an upwardly extending rim or flange 36 having threads 38 for securing a cylindrical hanger 40. The hanger 40 extends vertically upward from the seat anchor 30, and is provided at its uppermost 50 end with projections or shoulder portions 42 adapted to cooperate with shoulder portions 44 provided on the lowermost end of the housing 6 for a purpose as will be hereinafter set forth. The anchor 30 is provided with a reduced portion 55 46 having outer threads 48 for receiving a cylin-

der or pipe 49 extending to the bottom of the well hole. The seat 30 is provided with an aperture 50 having threads 52 for receiving a bushing 54 for a purpose as will be hereinafter set forth.

From the foregoing it will be apparent that the standing valve spider including the elongated cylinder 26 are not positively or directly connected to the working barrel housing 6, which in turn is directly connected to the tubing 4 by the collar 8. The standing valve structure is connected to the bottom seat anchor 30, which in turn is supported in the well by the lower cylinder 49 resting on the bottom of the shot hole. The cylinder 49 is provided with apertures 56 allowing discharge of oil from the shot hole therethrough. In cases where the oil in the shot hole is not sufficient to warrant the large cylinder 49, the bushing 54 can be removed and replaced with a smaller apertured cylinder (not shown) resting on the bottom of the well hole for supporting the seat anchor 30.

Operation

In the reciprocation of the plunger 10 by the sucker rods, the oil is periodically displaced through the valves 22 and 18 into the tubing 4 above the pump. On a down stroke of the plunger 10, the oil previously displaced above the valve 22 opens valve 18 for displacing the oil into the tubing 4 above the valve 18. During this movement of the plunger 10, the valve 22 is closed and all the weight of the oil previously displaced by actuation of the plunger 10 is on the standing valve 22, seat anchor 30 and cylinder 49. In this manner it will be seen that the floating connection between the housing 6, the standing valve spider 20, and valve 22 eliminates any positive or direct connection with the tubing 4, which in turn eliminates any possibility of the oil weight stretching the numerous sections of tubing disposed in the well hole. It will be apparent that the floating connection of the valve 22 likewise lengthens the plunger stroke, and prevents frictional drag of the tubing against the well casing. In a standing valve directly connected to the tubing, the oil weight stretches the tubing, and due to this tubing stretch or sag, the plunger stroke is shortened. On an upward stroke of the plunger, the tubing unstretches and returns to substantially normal. However, this reciprocating movement causes a wearing out of the tubing in places where it may contact the casing.

In a pulling operation the valve 18 and plunger 10 are pulled separately by the sucker rods for replacements and the like. When it is desired to remove the standing valve 22 and anchor 30 from the well hole, it is necessary to remove the tubing and housing 6. The shoulders 44 of the housing 6 in moving vertically upward contact the shoulders 42 of the hanger 40 to pull the anchor and its complementary structure from the well hole (see Fig. 2). The hanger 40, in a pulling operation, also acts as a guide for the working barrel housing. Furthermore, it will be noted that the pump housing 6 is provided with a plurality of apertures 58 which allow bleeding of the oil in a pulling operation.

Referring to Fig. 3 disclosing a modification, the seat anchor 30 of the preferred embodiment is eliminated, and the cylinder 62 of the standing valve spider 68 extends vertically downward in spaced relation to casing 63 and rests on the bottom of the shot hole for supporting the valve. The lowermost portion of the inner periphery of the housing 64 is provided with projections 66

which, in a pulling operation, are adapted to contact the lower face 68 of shoulders 70 for pulling the standing valve spider 68 and its cooperating structure from the well hole along with the housing 66. It will be apparent that in this modification all stretching or elongation is eliminated, since the standing valve is in no manner connected to the pump housing or tubing, but is supported by the cylinder 60.

Fig. 4 is a modified form of seat anchor utilized when it is desired to anchor the working barrel at some point in the casing other than in proximity of the bottom of the shot hole. The seat anchor 80 is provided with a threaded flange 82 for receiving a hanger 84 (partially shown) similar to the hanger as disclosed in the preferred embodiment. The seat 80 is likewise provided with an aperture 86 having threads 88 for receiving cylinder 90 (partially shown), and similar to the cylinder 26 of the preferred embodiment. The outer periphery of the seat 80 is provided with tapered portions 92 adapted to cooperate with tapered portions 94 of slips 96. The slips 96 are provided with outer serrations 98 for frictionally biting into the well casing 100 when in set position. Belly springs 102 extend downward from the slips for supporting them in the casing 100 prior to their radial expansion into biting engagement with the casing by the seat anchor 80. In Fig. 4 the slips are shown as being run separately in the casing. However, it will be apparent that they could be run in with the tubing in any conventional manner. Although not shown, it will be apparent that a standing valve spider and cylinder are arranged in the pump housing the same as in the preferred embodiment, so the weight of the oil displaced acts upon the seat 80 and slips 98 in lieu of the tubing, thus preventing any stretching of the tubing.

Changes may be made in the combination and arrangement of parts as heretofore set forth in the specification and shown in the drawings, it being understood that any modification in the precise embodiment of the invention may be made within the scope of the following claims without departing from the spirit of the invention.

What I claim is:

1. In combination with a tubing of an oil well, a pump housing secured to the lowermost section thereof, a plunger arranged for reciprocating movement through the uppermost portion of the housing, a travelling valve cooperating with the plunger, an inlet valve disposed below the plunger, said housing surrounding the inlet valve and adapted to telescope therewith, and means for supporting the inlet valve separate from the housing to prevent stretching of the tubing by the weight of the displaced oil.

2. In combination with a tubing of an oil well,

a pump housing secured to the lowermost section thereof, a plunger arranged for reciprocating movement through the upper portion of the housing, a travelling valve cooperating with the plunger, an inlet valve disposed below the plunger, said housing surrounding the inlet valve and adapted to telescope therewith, an apertured seat anchor arranged below the housing for supporting the inlet valve separate from the housing, an apertured cylinder secured to the seat anchor and resting on the bottom of the well for supporting the anchor, guide means secured to the anchor and adapted to surround the housing, and means on the guide cooperating with the means on the lowermost portion of the housing for removing the guide and anchor from the well.

3. In a bottom hole pump comprising a housing, a plunger arranged for reciprocating movement through the housing, a travelling valve co-operating with the plunger, an inlet valve spider disposed below the plunger, an inlet valve disposed in the spider, an elongated seat cooperating with the inlet valve, said housing surrounding the seat and valve and adapted to telescope therewith, means for supporting the inlet valve and

5 seat independent of the housing, means for supporting the last-mentioned means in the well hole, guide means secured to the supporting means, and means arranged on the guide means cooperating with the housing for removing the guide means and supporting means from the well hole.

CHARLES F. MOSELEY.
